UNITED STATES PATENT OFFICE.

NOYES F. PALMER, OF NEW YORK, N. Y.

HOPPER.

SPECIFICATION forming part of Letters Patent No. 734,740, dated July 28, 1903.

Application filed April 23, 1903. Serial No. 153,918. (No model.)

To all whom it may concern:

Be it known that I, NOYES F. PALMER, a citizen of the United States, residing at New York city, (Brooklyn,) county of Kings, and State of New York, have invented certain new and useful Improvements in Hoppers, of which the following is a specification.

This invention relates to a hopper for molds for making artificial stone and for similar purposes.

The hopper is so constructed that it may be readily taken apart and fitted to molds of different sizes and that it is properly reinforced at the corners and secured against displacement.

In the accompanying drawings, Figure 1 is a perspective view of part of a mold for making artificial stone provided with my improved hopper; Fig. 2, a cross-section on line 22, Fig. 1; Fig. 3, a perspective view of the corner-plate; Fig. 4, a bottom view thereof; and Fig. 5, a plan of the hopper, showing a nest of additional hoppers in dotted lines.

The hopper is composed, essentially, of four inclined sides or boards A and of four correspondingly-inclined angular corner-plates B. Each corner-plate is composed of a pair of wings b, having inwardly-extending ribs b'. These ribs are received by corresponding mortises in the lower edges of sides A, and thus extend flush with the inner face of the hopper, Fig. 1. The object of the ribs is to form a reinforcement for the sides at the inner corners of the hopper which are subjected to the greatest wear during the tamping operation. The corner-plates B are fitted over the adjoining upright edges of the sides A and are removably connected to such sides by bolts a. These bolts pass through corresponding holes in the sides and corner-plates, and by withdrawing them the hopper may be readily taken apart. One of the wings b of each corner-plate is provided with a downwardly-projecting lug b². This lug fits into a corresponding notch d' of a top plated, that

is flush with the mouth of the mold D and holds the hopper against lateral displacement.

At opposite sides of the hopper there are removably secured to the corner-plates B a pair of foot-bars e, that project laterally beyond the boards A. These bars are provided with a number of perforations e', either one of which is adapted for the reception of a bolt a, by which the foot-bar is secured to the hopper.

In use the hopper is fitted over the mouth of the mold with the lugs b² entering the notches d'. Two operators standing upon the plates d step upon the projecting ends of the bars e to prevent tilting of the hopper and then the concrete is filled in and tamped, as usual. After the operation has been completed the hopper is removed preparatory to the removal of the green stone.

It will be seen that my improved hopper may be readily taken apart and that the same corner-plates may be fitted to boards of different sizes. So, for example, in Fig. 5 I have shown a nest of three hoppers, each of which is composed of like corner-plates, while the sides vary in length. Thus by furnishing a mold with one set of corner-plates and with several sets of boards the operator may readily construct the different sizes of hopper required for the machine.

In taking the hopper apart the bolts are withdrawn to disconnect the foot-bars from the corner-plates and the latter from the sides. The corner-plates are then bolted to a new set of sides, and the foot-bars are bolted to the corner-plates, the bolts being inserted through those perforations e', which are now in alinement with the perforations of the corner-plates.

What I claim is—

1. A hopper composed of inclined recessed sides, and corner-plates bolted to said sides and having inwardly-extending ribs and downwardly-extending lugs, substantially as specified.

2. A hopper composed of inclined sides, corner-plates removably connected to said sides, and laterally-projecting foot-bars that are removably connected to the corner-plates, substantially as specified.
3. In a hopper, inclined recessed sides, combined with corner-plates bolted to said sides and having inwardly-extending ribs and downwardly-extending lugs, and with perforated foot-bars bolted to the corner-plates and projecting beyond the sides, substantially as specified.
- Signed by me, at New York city, (Manhattan,) New York, this 22d day of April, 1903.

NOYES F. PALMER.
